Dec. 1254

Birdsill Holly of Lockport, N.Y.
Letters Patent No 7556 dated June 16, 1860

The schedule referred to in these Letters Patent and making a part of the same;

To all whom it may concern:

Doth know that I, Birdsill Holly of Lockport in the County of Niagara, and the State of New York, have invented or produced a new design for the Top or Stock of Well Pumps; and I do hereby declare that the following is a full and exact description thereof, reference being had to the accompanying drawings, making part of this specification, in which -

Fig. 1. is a perspective view, and

Fig. 2. a front elevation of one of the side plates,

- Similar letters . . . . . designate corresponding parts in both of the figures.

My improved design for a pump top, consists of a rectangular frame, two sides of which consist of plates formed as represented in fig. 2, having arched feet a. a, which form the base, immediately above which three columns are carried up a short distance, when they unite and form two arched openings, B. B, which are filled with light tracery. Directly over the center pier is a large opening C, to receive the spout, on either side of which is a smaller opening, d. d, also arched, terminating with the top

32

and bottom of C. Above this the width of the — is diminished by a curve corresponding with the arch of the openings, and is occupied with two arched openings E. E. also filled with tracery; when the plate again diminishes with a curve as before described, and is occupied with one opening E, similar to the others, but of a reduced size. A small circular head, g. forms the apex, which, with the openings below, and the outer edges of the plate, are alike surrounded with a projecting bead, which gives boldness of effect to the design.

The lever H, has curves corresponding with those of the side plates, making it in harmony with the general appearance of the top, which is pyramidal. Its edges are also beaded.

An ornamental yoke K, fig: 1, forming a fulcrum for the lever, is composed of three semicircular sections L. L. L. united together, and connected with the axis, m., by two waving members, N. N.

The two side plates are joined together by four plain rods or bolts, two at the base, and two directly over the heads of the openings, d. d. leaving a space between of about two thirds of the width of the side plates, which readily accommodate the working parts of the pump, such as pipe or cylinder. The general appearance of the pump is compact and agreeable, indicating strength and adaptation to the purposes of its use, without ostentation or display.

What I claim as a new design for the Tops of Pumps, is the form and configuration of the side-plates as shown and described, and the combined configuration of the side plates with the transverse rods, lever and yoke; as described and shown in fig: 1. — 3
